UNITED STATES PATENT OFFICE.

NELSON H. FOOKS, OF PRESTON, MARYLAND.

VALVE.

1,327,540.

Specification of Letters Patent. Patented Jan. 6, 1920.

Application filed April 8, 1919. Serial No. 288,588.

To all whom it may concern:

Be it known that I, NELSON H. FOOKS, a citizen of the United States, residing at Preston, in the county of Caroline and State of Maryland, have invented certain new and useful Improvements in Valves; and I do hereby declare the following to be a full, clear, and exact description of the invention, such as will enable others skilled in the art to which it appertains to make and use the same.

This invention relates to fluid pressure control means, and more particularly to valves.

In certain types of apparatus there may be differential pressures as respect to closed chambers, or a closed chamber and other chambers, or as to the atmosphere. For instance, in the art of cooking goods in closed containers, such as tin cans, the canned goods are handled in divers processes, one of which consists of subjecting the cans to a suitable degree of temperature, and also at a pressure above atmospheric. Ordinarily closed, pressure cookers are charged with racks containing numbers of the cans, and the cooker or retort is then sealed and the temperature and pressure raised, and after the cooking has been completed, the pressure is removed, the cover opened, and the stacked goods removed, all of which process involves considerable loss of time and a waste of heat, and it has, therefore, been proposed to provide a continuous, pressure cooker, means being provided to control the entire discharge of the cans into and from the cooker, with a minimum loss of pressure from the cooker. This type of cooker involves, therefore, a form of feeding and withdrawing device, serving as a closure for the retort, as well as a carrier for the cans, and might be termed a valve.

It is one of the especial objects of the present invention to overcome the very material loss of pressure and waste of heat in various types of structures and apparatuses employing valves which intermittently open communication, as between two chambers having differential pressure, or as between one chamber and the atmosphere, and it is a further object of the invention to provide a pressure-controlling means in the form of a valve which is designed to so control the escape of pressure between the different mediums as to substantially eliminate any material direct exhaust or waste from the

higher pressure medium to the lower pressure side, and thus to accomplish an object of the invention, which consists in the conservation of heat or pressure, and in the economical use of moisture if liquid is utilized in the operation of the process in which the organization or apparatus may be employed.

Differently stated, it is an object of the present invention to provide a valve so designed, constructed and operative as to successively reduce by a plurality of steps, volumes of fluid or gas commencing at a degree of pressure at one point of the valve equal to that in the high-pressure chamber of the apparatus, and thence stepping down the pressure toward the outlet or exhaust side of the valve to such a degree that the exhaust differential has been minimized to the degree desirable or practicable.

It is further an object of the invention to improve the construction of valves so as to enable the use thereof as a medium for controlling the eduction of fluid under pressure, as between differential pressure sides, and at the same time to enable the use of the valve as a conveyer or carrier for introducing into or withdrawing from an element of the apparatus, various objects to be handled in the operation of or which are acted upon during the use of the apparatus. A further object of the invention is to improve the mounting arrangement of the valve, and the packing instrumentalities thereof, so as to prevent leakage of the fluid as far as practicable.

With these, and other objects in view, as will be rendered manifest to those versed in the art, the invention consists of the construction, the combination, and in details and arrangements of the parts as more particularly described in the following specification relative to the form of the invention shown in the accompanying drawings, wherein:

Figure 1 is a side elevation, with parts broken away and also partly in section, representing one adaptation of the improved valve.

Fig. 2 is a section on line 2—2 of Fig. 1. 105

Fig. 3 is an enlarged, detailed view of the packing means and associated parts.

Fig. 4 is a view on the same scale of means for pressing a packing ring into bearing contact with the valve.

In the embodiment of the valve shown in Fig. 1, the valve structure comprises a wheel-

100

110

like member 75, of suitable proportions and design of construction, and its perimeter is shown as provided with a series or plurality of pockets 32, between each of which there is formed a high or ridge point 77, the extreme ends of which lie substantially in a circle closely approximating the bore of the casing 78, and preferably these high points are provided with transverse packing bars 79, which are arranged in respective recesses therefor, and these are yieldingly pressed outwardly by respective pairs of springs 80, surrounding pins 81, which enter pockets 82 in the rim portion of the wheel 75, and passing therethrough to receive lock nuts 83 on their exposed ends. Preferably each side of the wheel 75 has secured to it a disk 84, the outer faces of which are ground to run smoothly against the adjacent plane faces of the chamber 78, and the packing strips or pieces 79 are shown plainly in Fig. 3, as extending through the rims of the side disks or plates 84. To prevent leakage of pressure, which will be introduced, as hereinafter described, around and along the edges of the side disks 84, and between the adjacent faces of the casing 78, which, as shown in Fig. 2, is provided with one removable side 78', the casing is provided with an annular recess indicated at 85; on each side in each recess, there is inserted a split and resilient packing ring 86, having a cross-sectional contour and area closely approximating the cross-sectional form of the recess 85, and for the purpose of pressing each ring 86 against the adjacent side of the rotating valve disk 84, suitable means are employed, one form of which consists of a series of expansion springs 87, arranged in respective pockets 88', formed in the sides of the casing 78, and these springs obviously made in suitable number, and such distribution as to secure the even and desired degree of pressure throughout the ring against the valve disk.

The valve structure and its casing, as just described, is shown in the present case as mounted upon one side of a chamber indicated at 2, and which may represent the chamber, within which suitable conveying means as the angle slats 37 arranged, for instance, on wheels which form a carrier for cans, indicated at C. When pressure is created in the container 2, to facilitate a cooking of the contents of the cans, it is especially desirable to prevent the loss of pressure from the chamber 2, as the cans are successively introduced thereinto, and the present valve with its casing, when attached to the chamber 2, permits the successive introduction of cans from any suitable source of supply into the chamber 2, with the minimum loss of pressure, as will now be described. The lower portion of the casing 78 is provided with an outlet 21, and an upper

portion with an inlet 33, and the valve 75 is shown as provided with, say, twelve pockets designated at 32, which will successively pass below the inlet and supply means, and also successively pass the discharge outlet 70 so that the cans will be deposited on the carrier slats 37. By providing a plurality of the pockets 32, as in this embodiment of the invention it is possible for me to reduce the pressure as between that in the chamber 75 and that without the inlet side 33 of the casing 78 in a number of successive and decreasing degrees, until finally the pressure in a pocket will, when the latter reaches the inlet of the chamber 78, have been so reduced 80 as to be substantially equal to the pressure at the inlet, or if desired, be in excess thereof.

I secure this feature of successively reducing the pressure in the valve pockets, by 85 the following means, which illustrate one manner of securing the desired results. Each of the pockets 32 is provided with a port, or if desired, with ports, and in this case the port, designated at 88, for each 90 pocket is formed in one of the side disks 84 at a suitable location with respect to the contour of the pocket, and preferably disaligned from the portion of the pocket in which the can C normally rests. The entire series of ports 88 is preferably arranged in a circle concentric to the shaft of the valve, and which latter is manifestly geared with respect to the carrier mechanism, so that the slats 37, thereof, are timed to come 100 to the outlet of the casing 78 in proper relation to the pockets 32 thereof, so that a can can be released from the carrier of valve 75, to be timely discharged on to a registering slat 37 of the carrier in the chamber 2. That 105 side or end wall of the casing 78, which covers the disk 84, which is provided with the ports 88, and which is illustrated in Fig. 1, is provided with a series of ports entered by the ends of transfer pipes 89, which 110 are slidably mounted in bearings therefor, and preferably provided with packing means 90, the ends of the pipes 89 being tapped or otherwise secured in the adjacent sides of the packing ring 86, and which latter is also provided with ports 91 disposed in a circle coincident with the circle in which the series of ports 88 lie in the adjacent disks 84. The transfer pipes 89 are preferably slidable in their bearings, and 115 are cross-connected as from one side of the casing 78, as at x, to the opposite side as y, the connecting pipes 92 between a given pair of the end pipes 89 being disposed as follows: As one of the pockets 32 passes the 120 can outlet at the bottom of the chamber 78, and a can issues therefrom, this pocket thence crosses the opening or gap in the casing, and moves into juxtaposition with a portion of the annular wall of the casing, 130

which is of sufficient length to cover a pocket and provide bearing face for an adjacent pair of the packing strips 79. This being so, there is then in this pocket, which 5 has just left the outlet opening, a pressure equal to the pressure in the container or chamber 2. Now by placing one of the transfer and end pipes 89, with its port 91, at such area of the casing 78 as forms a 10 wholly closed chamber, as soon as a pocket 32 leaves the outlet opening, then it will be possible to discharge the compressed fluid therefrom to the opposite side of the casing, and of its outlet at a point indicated at *k*, 15 where the pressure will blow through the cross pipe 92, when a port 88 of the side disk 84 registers with the port 91 in the ring 86 of the end or transfer pipe 89. This transfer of pressure from one closed pocket 20 leaving the outlet of the chamber across to another pocket having a lower pressure, and immediately approaching the outlet of the chamber, will obviously cause an equalization of pressure in the pockets, which 25 momentarily are placed in intercommunication by the first step or transfer pipe nearest the outlet. Now if the pocket passes from the first stage of reduction farther along in the same direction to the next stage, the pressure 30 therein can also be reduced another step, since the port 88 thereof reaches the registering end as *j*, of the next reduction pipe 92, and pressure will be reduced as a pocket at *j* is placed in communication with another pocket on the other side of the casing, and indicated at *m*; this gives a second reduction. Obviously the number of steps of reduction can be continued, and will be 35 determined by the number of pockets 32 in a valve, as the pressure in the given pocket is successively decreased, as this pocket passes from the outlet at the bottom of the chamber 78, which will ultimately be brought into juxtaposition with the exhaust 40 43, and any pressure residing in the given pocket above the pressure in the exhaust passage will therefore be released. Conversely, if the pressure in a given pocket is 45 successively stepped down as it reaches the exhaust 43, the pressure in the given pocket moving down with a can in the opening will be successively increased by the successive transfer of pressure through the different transfer pipes 92, and therefore, not 50 only is there an economy in the reduction of the pressure of exhaust, but there is also an increase of the pressure in the pockets moving toward the outlet connecting the casing 78, and the container 2, and obviously 55 the highest pressure in a pocket moving to the can outlet of the chamber 78, is accomplished just prior to the movement of a pocket into the can outlet passageway. By this form of construction, and mode of operation, it will be seen that there is a sub-

stantial balance of pressure on the opposite sides of the valve, and therefore, pressure resistance is overcome, but again, any condensed moisture, which may be carried into the outgoing pockets 32, collects in the incoming pockets, and restored to the chamber 2 and further it will be seen that when the valve 75 is used to convey cans to the cooker, that the cans will be successively subjected to increasing degrees of temperature and 70 pressure. While I have shown the valve 75, as adapted to supplying cans to the cooking apparatus, it is readily adaptable to the use of conveying cans from the cooker.

It will be observed from the above that by 80 using a valve structure having a plurality of chambers which are successively registered with a higher pressure port and later with an exhaust, that an economy of pressure is obtained by successively equalizing the pressure in given series of the chambers, as by connecting one of the charged chambers leaving the pressure port and while this pocket is closed connecting it to another closed pocket moving from the exhaust port 90 and toward the pressure port so that the medium is restored to the pressure chamber with but a minimum loss of pressure. Moreover it will be seen that by successively equalizing the pressure in multiple stages of 95 different degrees of pressure the chamber approaching the exhaust or outlet has been depleted of pressure to a given degree and at the same time a chamber leaving the exhaust is replenished gradually as it approaches the pressure port and this by the pressure taken from the port.

What I claim is—

1. A device for conveying material between atmospheres of different pressure and 105 for controlling the flow of fluid under pressure between the different atmospheres, this device having a carrier with pockets to receive the material, and means for connecting certain pockets in successive steps of their 110 movement to reduce the higher pressure in successive stages toward the lower.

2. A valve between atmospheres of different pressures comprising successive fractioning means to vary the pressures between the 115 high pressure atmosphere and the low pressure atmosphere.

3. A conveyer structure comprising a housing provided with an inlet and an outlet, and a member movable within said housing 120 provided with object carrying and expansion pockets, and means for selective intercommunication between said pockets to successively vary pressure in said pockets.

4. In a conveyer structure, relatively movable members forming a plurality of chambers, an inlet and an outlet, and means arranged to effect the transfer of fluid pressure between certain of the chambers during the operation of the apparatus, and compris- 125 130

- ing ports connected in series of independent groups, including one port to open communication between one chamber moving toward the inlet and one moving toward the 5 outlet.
5. In a conveyer structure, relatively movable members forming a plurality of closed chambers, an inlet and an outlet, a packing ring having series of ports, one of said members also having series of ports to register therewith during operation of the valve, and means connecting groups of ports in the ring to effect successive reduction of pressure in the chambers as respective ports 10 register.
6. In a continuous, pressure cooker a chamber having can feeding means therein, a valve with can receiving pockets, said pockets enlarged forward of said can in its 15 direction of movement, said valve forming a closure for the opening to the interior mechanism, and means for equalizing the pressure of fluid in certain of the pockets during operation of the valve, the pressure 20 being materially reduced by expansion in said pockets.
7. In a continuous, pressure cooker a chamber having can feeding means therein, a valve with can receiving pockets materially larger than the cans, said valve forming a closure for the opening to the interior mechanism, and means for equalizing the pressure of fluid in certain of the pockets during operation of the valve for the purpose 25 of materially reducing the exhaust pressure from the valve and for differentiating pressure on the cans in a plurality of stages.
8. In combination, a pressure cooker, a valve between said cooker and another atmosphere for varying the pressure between said cooker and said atmosphere, said valve provided with chambers and means to successively fraction pressure in said chambers 40 between said cooker and said other atmosphere.
9. In a continuous pressure cooker a chamber having can feeding means therein, a valve with can receiving pockets, said 45 valve forming a closure for the opening to the interior mechanism, and means for materially reducing and equalizing the pressure of fluid in certain of the pockets during operation of the valve for the purpose of greatly reducing the exhaust pressure from the valve and for differentiating pressure on the cans gradually, the differentiation 50 occurring in successive steps.
10. In an apparatus having a normally closed chamber to and from which articles are passed, an inclosed transferring valve having a series of pockets, and means for interconnecting the pockets in independent sets upon relative movement of the valve in 55 its casing.
11. In combination, a carrier provided with fluid tight pockets, a housing surrounding said carrier, conduits interconnecting said pockets in independent sets upon the relative movement of said carrier in said casing, said conduits so arranged that pressure in certain pockets is successively reduced while pressure in other pockets is successively increased.
12. In an apparatus having a normally closed chamber to and from which articles are passed, an inclosed transferring valve having a series of pockets, and means for interconnecting the pockets in independent sets upon relative movement of the valve in its casing, said means so arranged that the greater pressure is gradually stepped down from one side of the valve to the other where communication is made to the lowermost pressure side.
13. An apparatus having a normally closed chamber to and from which articles are passed, an inclosed transferring valve having an inlet and an outlet through its closure for permitting the inlet and outlet of the articles to atmospheres of different pressures, the valve having a series of article receiving pockets which with the inclosure or moving chambers to be brought successively into register with the inlet and with the outlet, and means constructed and arranged to equalize the pressure in pairs of the pockets or chambers as they are successively brought to register with the high pressure side of the valve, one of the said pockets being at the time of equalization on each side of the high pressure opening, said means providing for the reduction of the pressure in the pockets in successive stages in those pockets between the higher pressure side and the lowest pressure side.
14. An apparatus having a normally closed chamber to and from which articles are passed from a space-pressure different from that in the chamber, a conveying valve organization including a valve and a closure or casing therefor between which there are formed a number of article receiving pockets or chambers, and an inlet and an outlet for the articles successively to the said chambers; and means for independently connecting said pockets or chambers in sets so as to equalize the pressure as the sets become interconnected and whereby the pressure is reduced in successive steps from the highest pressure to the lowest pressure involved.
15. An apparatus having a normally closed chamber to and from which articles are passed from a space-pressure different from that in the chamber, a conveying valve organization including a valve and a closure or casing therefor between which there are formed a number of article receiving pockets or chambers, and an inlet and an outlet

for the articles successively to the said chambers; and means for independently connecting said pockets or chambers in sets so as to equalize the pressure as the sets become interconnected and whereby the pressure is reduced in successive steps from the highest pressure to the lowest pressure involved, the pressure reducing means being so arranged and disposed that the pressure is gradually increased in those of the pockets that are moved toward the higher pressure side while the pressure in those pockets moving away from the higher pressure side is successively reduced.

16. In combination, a housing, a rotor within said housing, said housing provided with apertures for receiving and discharging materials to and from said rotor, said rotor provided with pockets for carrying material between said apertures, said pockets packed relative to said housing to form expansion chambers and having a receiving contour conforming to the shape of said materials to be carried therein and said pockets also having an inclined plane for-

ward of said pockets and leading to said pockets and a shoulder between said pockets and said plane.

17. In a valve mechanism for delivering cans into a cooker, a rotor, a casing for said rotor, said rotor provided with pockets, and means within said casing for gradually admitting said cans into said pockets. 30

18. A valve mechanism for delivering cans into a cooker comprising a rotor provided with pockets, a casing surrounding said rotor, and means for gradually admitting cans into said pockets, said means including a gradual incline in said rotor so that the cans may be seated in the bottom of the 40 pockets when they reach the end of the incline.

19. In a valve, a rotor provided with pockets, a casing surrounding said rotor, said casing provided with apertures, and an 45 incline to said pockets, the dividing line between a pocket and said incline forming a shoulder.

In testimony whereof I affix my signature.
NELSON H. FOOKS.
